(57) **CLAIM**

The ornamental design for a hand control, as shown and described.

DESCRIPTION

FIG. 1 is a front, right, bottom perspective view of a first embodiment of a hand control showing my new design;

FIG. 2 is a rear, right, bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line showing is for the purpose of illustrating unclaimed portions of the article and forms no part of the claimed design.
